UNITED STATES PATENT OFFICE.

JOSEPH E. SCHAEFER, JR., OF DETROIT, MICHIGAN, ASSIGNOR, BY MESNE ASSIGNMENTS, TO AMERICAN IGNITION COMPANY, OF DETROIT, MICHIGAN, A CORPORATION OF MICHIGAN.

TERMINAL-ATTACHMENT-ENGAGING DEVICE.

1,024,601.

Specification of Letters Patent. Patented Apr. 30, 1912.

Application filed August 18, 1910. Serial No. 577,792.

To all whom it may concern:

Be it known that I, JOSEPH E. SCHAEFER, Jr., a citizen of the United States of America, residing at Detroit, in the county of Wayne and State of Michigan, have invented certain new and useful Improvements in Terminal - Attachment - Engaging Devices; and I hereby declare the following to be a full, clear, and exact description 10 of the invention, such as will enable others skilled in the art to which it pertains to make and use the same.

This invention relates to an improved terminal attachment engaging device for 15 spark plugs.

The object of this invention is to provide a universal member which can be applied to any spark plug and which will serve as an ordinary binding nut and also be able 20 to engage with the various special terminal attachments now on the market.

My invention, therefore, consists in the features of construction and combination of parts described in the specification, pointed 25 out in the claims and illustrated in the accompanying drawings.

Much trouble in operating an explosive engine results from the terminal of the electric circuit breaking away from its connection with the spark plug which of course is due to the constant jarring of the engine. The simplest form of connection consists of a nut which is adapted to screw on to the spindle of the spark plug and clamp the 30 end of the wire against another nut or a shoulder on the spindle. As this connection has not proved satisfactory a number of special terminal attachments have been placed on the market. These terminal attachments are permanently secured to the 35 end of the electric wire and there must be a corresponding special attachment on the spark plug. It therefore frequently happens that when a new spark plug is employed 40 the terminal of the battery cannot be connected thereto. In order to overcome this difficulty I provide a member adapted to be mounted on any spark plug and constructed so that it will engage with or be engaged by 45 the various attachments for terminals now on the market.

In the accompanying drawings Figure 1 is

an elevation of a spark plug provided with my improved device. Fig. 2 is an enlarged central section through the device and a portion of the spark plug.

Again referring to the drawings 1 and 2 represent the two sections which form the outer casing of the spark plug and which are secured together in the usual manner. 60 The section 2 is provided with the usual screw thread 3. Within the casing is arranged the usual spindle 4 which projects beyond the end of the section 1 and the projecting end of the spindle is threaded as 65 shown at 5.

My terminal attachment engaging member comprises a nut 6 which is adapted to screw onto the end of the spindle 4, a washer 7 being preferably arranged between the 70 end of the section 1 and the nut 6. On the top of the nut 6 is formed an integral extension which consists of a neck portion 8 which swells up to a spherical shaped portion 9 which is topped by a cylindrical portion 10. In the spherical shaped portion is 75 formed an annular groove 11.

The use of the device is as follows.—If the end of the wire which is to be attached to the spark plug is not provided with any special attachment the end thereof is simply placed under the washer 7 and the nut 6 is turned down thereon. If the end of the wire be provided with an attachment consisting of 80 forked blades provided with sockets, the 85 blades are sprung over the spherical portion of the device. If the end of the wire is provided with a split ring attachment the ring is forced into the groove 11 in the spherical portion of the device and if the end of the 90 wire is provided with a closed ring attachment the ring is forced down over the cylindrical portion 10.

What I claim is,—

1. A terminal attachment engaging device 95 consisting of a nut provided with an extension, the portion of said extension adjacent to the nut being spherical shaped and the upper end of said extension being cylindrical shaped, the said spherical shaped portion being provided with a circumferential slot at the upper end adjacent to the cylindrical portion.

2. A terminal attachment engaging device

consisting of a nut provided with an extension, one portion of which is cylindrical shaped and the other portion spherical shaped, the said spherical portion being provided with a circumferential slot, for the purpose set forth.

In testimony whereof, I sign the forego-

ing specification, in the presence of two witnesses.

JOSEPH E. SCHAEFER, JR.
